UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

METAL-WORKING MACHINE.

Application filed February 20, 1923. Serial No. 620,210.

To all whom it may concern:

Be it known that ROBERT S. BROWN, citizen of the United States, residing at New Britain, in the county of Hartford and 5 State of Connecticut, has invented certain new and useful Improvements in Metal-Working Machines, of which the following is a specification.

This invention relates to metal-working 10 machines, and in that form of embodiment of the invention which I have selected for illustration in the drawings accompanying and forming part of the present specification, the machine takes the form of an automatic screw machine, the improvement 15 being particularly in means for chucking irregular work in a moving spindle.

Among the objects of the invention are 20 the provision in a machine of the character set forth, of means by which work of irregular character such as nut-blanks can be chucking into a moving spindle. What is 25 illustrated in the drawings will be set forth fully in the following description so that those skilled in the art can practice the invention. However, I am not restricted to 30 such disclosure. I may depart therefrom in a number of respects within the scope of the invention defined by the claims following said description.

In Letters Patent No. 1,177,827 issued April 4, 1916, to Christopher M. Spencer, and assigned to The New Britain Machine Company, is shown a machine of the general type in which the present invention is 35 incorporated and in Fig. 1 of the annexed drawings, I have shown more or less fully, such a machine.

It will be noted that while primarily my 40 improvements are especially adapted for incorporation in machines of this general type, I am in no sense, however, restricted thereto.

Referring to said drawings:

Figure 1 is a side elevation of a metal-working machine involving the invention.

Fig. 2 is a side view on a somewhat larger scale of work-positioning means, several work-spindles and tool-spindles being 50 shown.

Fig. 3 is a sectional end elevation as seen for example from the right in Fig. 2.

Fig. 4 is a vertical section on the line

4—4 of Fig. 3, looking in the direction of the arrows. 55

Fig. 5 is a section virtually like Fig. 4 but with the work-holding spindle moved backward or in its initial position.

Fig. 6 is a practically similar view to Fig. 4 but showing the work-holding spindle in 60 a second stage of its operation or showing the work as having been thrust into a work-holding spindle.

Fig. 7 is a cross section on the line 7—7 of Fig. 3, looking in the direction of the 65 arrows.

Fig. 8 is a cross section on the line 8—8 of Fig. 4, looking in the direction of the arrows.

Fig. 9 is a cross section on the line 9—9 70 of Fig. 4, looking in the direction of the arrows.

Fig. 10 is a cross section on the line 10—10 of Fig. 4 looking in the direction of the 75 arrows.

Fig. 11 is a cross section on the line 11—11 of Fig. 6 looking in the direction of the arrows.

Like characters refer to like parts throughout the several views. 80

Referring first to Figure 1. I have shown in side elevation a somewhat complete illustration of a metal working machine which as represented is in the form of an automatic screw machine, so-called. Such a 85 screw machine involves a frame-work such as that denoted in a general way by 2 and which as shown comprises a base or bed 3, which has bolted or otherwise fastened to its upper side, a standard as 4, the standard 90 as shown comprising several uprights as 5 which sustain the main shaft 6 which runs lengthwise of the machine or of the frame work 2. The two uprights 5 at the left are connected at their top by a table 7 which 95 carries a work-head such as 8. This work-head 8 is rotative and as shown it sustains several work spindles as 9. It should be noted at this point that the head 8 is given an intermittent or step by step rotation and that the work-spindles 9 supported thereby, are given a rotation. During this rotation of the work-spindles, work is introduced into collets or work carriers at the forward or inner ends thereof and as the head turns, 100 the spindles carrying the work, position the

work, so that it can be acted on by tools, practically in the manner set forth in the Spencer patent which I have already identified.

The invention particularly resides in the positioning of work of irregular formation in cross section which has heretofore been difficult to position. By the present machine, however, I can position this work while the machine is in normal running action.

There are generally six of the work spindles 9 on the work-head 8, and a detailed description of one of them will, of course, apply to the others. Each work spindle incloses for longitudinal movement therein an endwise moving rod or bar 10 which is surrounded by the tube 11. The work spindles 9 have at their forward end each a head 12 as shown in Fig. 4, and the forward wall of which has a conical seat 13 to receive for sliding movement the jaws 14 which are intended to receive work of irregular form in cross section. The work strikes the plunger 15 which extends into the jaws 14 and which projects from a tube 16 which is attached by a pin as 17 to each bar or rod 10 near the forward end thereof as represented in Fig. 4. The plunger 15 has on it a shoulder 18 which slides in the tube 16. The rear end portion of the plunger 15 is surrounded by a coiled spring as 19 bearing at its front end against the shoulder 18 and at its rear end against the front end of the rod 10, as clearly shown in Fig. 4.

When a piece of work, such for instance as a nut blank, is introduced between the jaws 14, the work strikes the front end of the plunger 15 which thrusts the plunger 40 rearwardly or toward the left in Fig. 4 and slightly compresses the spring 19 so that when the jaws 14 are afterwards opened the reacting spring can eject the work from the jaws 14. It might be explained at this point that the work ordinarily of polygonal form in cross section is thrust between the jaws 14 and against the front end of the plunger 15 after which the jaws 14 are closed upon the work, the head 12 as it rotates, bringing the work around to position where it can be acted upon by the tools of the tool spindles.

It will probably be understood from foregoing description that the head 8 is rotated intermittently or step by step, and during such action the work-spindles are being rotated and during the rotation of the spindles the work is introduced thereto as will be hereinafter explained, and at a proper point this work is subjected to the action of tools such as 20 and 21 carried at the forward ends of the tool spindles as 22 supported by the carrier as 23, see Figs. 1 and 2. The work is introduced practically 65 automatically into the jaws 14 and the

means by which it is possible will be hereinafter set forth. The head 8 then rotates so that the work can be brought under the action of the tools 20, 21, etc., after which the work is automatically ejected in a finished state from the jaws 14.

There is coaxial with each work spindle, when it comes to a state of rest at the bottom, as shown for instance in Figs. 1 and 2, a spindle as 24, and which is given an endwise movement so as to feed the work carried thereby between the jaws 14 at the front end of the work-spindle, the spindle 24 having work-holding means such as shown by Figs. 2, 4 and 6. The spindle 24 incloses as shown in Fig. 6 an endwise movable rod 25. Said spindle 24 at its forward end on the left side as shown in Figs. 5 and 6 extends into a casing or guard 26, the outer wall of which has an opening 27 through which the head 28 of the spindle 24 is extensible in either direction, toward the left, its advance movement in Fig. 6, or toward the right, its retractive movement in Fig. 5. The head 28 supports the gripping levers 29. As shown, these gripping levers 29 have upon their inner sides complementary arms 30 which are pivoted at their inner ends as at 31 to the head 28, the arms 30 back of their pivot being slotted as at 32 to receive the guide pins 33 as shown in said Figs. 6 and 8. The forward ends of the gripping levers 29 are opened by hand as I will hereinafter set forth at which point a blank is inserted also by hand between the opened jaws of the levers which close when the levers are freed so that the levers are caused to grip the blank to introduce it into the jaws 14 as shown for instance by Fig. 4.

To rotate the work-carrying spindles, and the work-introducing spindles 24 in unison, the following mechanism may be utilized. Upon the work-spindle, as shown, in Fig. 4, is attached a gear wheel 34 which can be rigidly clamped thereon in any suitable manner. The peripheral teeth of the gear 34 are in mesh with the peripheral teeth of a gear 36 fastened to the shaft 37. It should be remembered that the action of the friction bevel discs 35 and 44 (Fig. 4) will be to bring the work from a state of rest without shock to initial rotative speed faster than that of the work-spindle 12. By forward movement of the handle 40, the friction discs are moved out of contact with each other so that the speed of the spindle 24 will be picked up by the pawl and will be rotated exactly in speed with the spindle 12. It will be understood that the contour of the piece to be tapped may register in only one position with the spindle and yet be properly inserted. It will also be probably understood that when the friction discs are in contact, the spindle will rotate at a high speed somewhat faster than

that of the work spindle. When the discs are in contact, the spindle has a tendency to lag, its speed of rotation being picked up, however, by the pawl 46 so that it will rotate exactly at the spindle speed.

There is rotative with said shaft 37 the spur gear 38 as clearly shown in Fig. 4. As represented, said spur gear 38 is fastened to a friction disk as 35, the hub of which 5 is splined to the shaft 37. In mesh with the gear 38 is the gear 39 inclosed by the guard 26. This spur gear is carried by the spindle 24 and when the parts are in normal condition, it is free to rotate upon the spindle. When the spindle 24 is moved toward a work-spindle, a certain distance, the gear 39, is by mechanism associated with the spindle 24, caused to rotate as will be hereinafter set forth. In the position shown in 10 Fig. 4, the spindle 24 is at rest while the spur gear 39 is rotating upon the same. Upon a diagonally extending shaft as 39' supported by the member 23 of the machine is fastened at the upper end thereof the 15 handle 40 for turning said shaft. The pinion gear 41 is fastened to the lower end of said shaft and is in mesh with the teeth of the rack 42 upon the sleeve 43. When the shaft 39' is turned by the hand lever 20 40 connected therewith, the gear 41 will be rotated so as to move the rack 42 rearwardly. This rearward movement of the rack 42 causes the friction disk 44 to be brought into contact with the friction disk 25 25 35. This owing to the difference in diameters will cause the spindle 24 to rotate faster than the work spindle. When this is accomplished, the rotating spindle 24 is moved forward or toward the work-spindle 30 as by the hand lever 40. Upon the front of the gear 39, and which, of course, rotates with the gear 39, is pivotally mounted a pawl or dog 46 which is held at its point or tooth against the exterior of the sleeve 35 45 or hollow shaft 45. When the gear 39 rotates, the pawl 46 revolves around the sleeve or hollow shaft 45. Said sleeve or hollow shaft 45 has in it the key-way 47. When the shaft 45 is moved forward or advanced, the point or tooth of the pawl 46 40 45 is thrust into the key-way 47 as shown in Fig. 11 by the spring 44 whereby the revolving pawl will now rotate the hollow shaft 45 so that if a blank 48 be introduced 50 between the levers 29, it will be thrust between the jaws 14 of the work-spindle and against the spring-actuated bar 15, the work-holder 24 at this time rotating at the same speed and in exact registry with the irregular opening in the jaws 14 which correspond of course with the blank 48. When the work-holder 24 has advanced to a point 55 where the blank is entering the jaws, the encircling collar 49 comes in contact with 60 the washer 50 on the rear end of the rod 65

25 and holding the said rod from any further advance. A continued advance of the work-holder or spindle 24, however, will cause the fingers 29 to move out of holding engagement with the blank as can clearly be seen by referring to Fig. 6.

Although the action of the machine will undoubtedly be readily understood, it may not be amiss to refer briefly to the same.

Initially with the parts in the position shown in Fig. 1, the drum or work-carrier 8 and the spindle 24 are assumed to be at rest. When the parts are in this relation, a piece of work will be introduced between the work-holding parts of the levers 29, the hollow shaft 24 at this time being back, as shown in Fig. 5, for instance. The handle 40 is now grasped and turned backwardly, thus rotating the shaft 39 and the pinion 41 so as to draw back the rack 42 and thus carry the friction clutch member 44 against the friction clutch member 45, and cause the rotation of the shaft 24. The handle 40 is then moved oppositely, thus advancing the shaft 25 or moving it toward the left in 75 Figs. 5 and 7 under the action of the pinion 41 and thus carrying the disk or clutch member 44 out of contact with the disk or clutch member 45, with a piece of work between the levers 29. The pawl 46 is being 80 revolved by reason of its being carried by the clutch member 44. During the normal action of the machine or when the spindle 25 is in the backward relation, the pawl 46 rides idly over the hollow shaft 45 without 85 accomplishing anything. When, however, the hollow shaft 45 has been moved sufficiently forward to permit the pawl to jump into the channel 47, the pawl 46 rotates the 90 hollow shaft 44, and thus causes the rotation of the levers 29, the action continuing, with work between the levers as shown in 95 Fig. 4, until the work is introduced between the jaws 14 as represented in Fig. 6 during 100 which action the shaft 24 is being rotated by 105 the pawl 46. Upon drawing the hollow shaft 44 backwardly, the conditions are exactly reversed.

In the annexed drawings, and in the foregoing description, I have disclosed quite fully a construction involving my invention. In no sense, am I restricted to the disclosure made thereby, as the invention involves certain broad relations as will be set forth in my claims.

What I claim is:

1. The combination of a rotary spindle, having a work-holder, of a second spindle having work-carrying means, driving and driven discs, the driving discs being constantly rotative, means to present work to the work-carrying means, means for endwise moving the second spindle to present the work carried thereby to the work-holder and means for driving the second spindle 115 120 125 130

at a speed approximately agreeing with that of the rotary spindle at the time the work carried by the rotary spindle is presented to the work-holder.

5. The combination of a rotary spindle, having a work-holder, of a second spindle having work-carrying means, means for causing an advance and a retractive movement of the second spindle, the work-carrying means on the advance movement presenting work from the work-carrying means to the work-holder, means for effecting the rotation of the second spindle initially at a

rapid speed with respect to the rotary spindle and thereafter in exact speed of the rotary spindle, and means for throwing out of action the second spindle by which the exact rotation of the rotary spindle with respect to the second spindle is effected. 15

In testimony whereof I hereby affix my 20 signature.

ROBERT S. BROWN.
